UNITED STATES PATENT OFFICE.

JOHN McGRATH, OF CLEVELAND, OHIO.

DESIGN FOR A COMBINATION LAMP AND LICENSE-TAG BRACKET.

41,972.

Specification for Design.

Patented Dec. 12, 1911.

Application filed September 8, 1911. Serial No. 648,406. Term of patent 14 years.

To all whom it may concern:

Be it known that I, JOHN McGRATH, a resident of Cleveland, in the county of Cuyahoga and State of Ohio, have invented a new, original, and ornamental Design for Combination Lamp and License-Tag Brackets, of which the following is a specification, reference being had to the accompanying drawing, forming part thereof.

The figure is a perspective view of a combination lamp and license tag bracket embodying my new design.

I claim:

The ornamental design for a combination lamp and license tag bracket as shown.

In testimony whereof, I have hereunto set my hand.

JOHN McGRATH.
